COMBINED CROWN AND TRAVELING BLOCK

Harry T. Nichols, San Antonio, Tex.

Application August 24, 1927, Serial No. 215,059

40 Claims. (Cl. 254—190)

My invention relates to hoisting apparatus for derricks. It has to do, particularly, with a compound pulley hoisting apparatus especially adapted for use in connection with the drilling of wells, although it is not necessarily limited thereto.

In the past the use of compound pulleys embodying fixed or standing block units, and running or traveling block units, with a multiplicity of parts or plies of a hoisting line rove to the sheaves thereof has been subject to certain serious disadvantages, partly due to the manner of mounting the sheaves thereof with relation to each other and partly due to the method of reeving the hoisting line therethrough.

One of these disadvantages has been the inability to obtain a balanced arrangement effective to ensure that the traveling block will not tilt during operation.

This tilting tendency is scarcely noticeable in a two-sheave traveling block, due to the proportionate rotational speed of the sheaves of two to one with four running parts rove and the standing part secured other than on the tackle block, and of five to three with five parts rove including the standing part secured to the tackle block, inherent when the block is rove with the parts of a line in direct sequence and is operated by a pulling force applied to the fall part of the line.

In a three-sheave traveling block, however, when rove with the parts of a line in direct sequence from one outer sheave to an intermediate sheave and thence to the other outer sheave, and operated by a pulling force applied to the fall part of the line, this tilting tendency is distinctly operative and correspondingly disadvantageous, due to the greater divergence in the proportionate rotational speed of the outer sheaves.

This disadvantage, which is cumulative in proportion to the number of sheaves thus rove, has, in all apparatus comprising more than two sheaves in the traveling block and which has been adaptable to and hitherto utilized in well drilling practice, resulted in seriously retarding and interfering with the speed of drilling operations.

During certain phases of the drilling operations the traveling block is raised from a position adjacent to the floor of the derrick to a position adjacent to the top thereof without a load, and conversely, during other phases of the operations it is lowered from the top of the derrick without a load.

It is when the traveling block is operated without a load, and particularly when it is being lowered without a load, that this disadvantage is

most acutely experienced, it being necessary to restrict the speed of operation in order to prevent the traveling block from excessive swaying and even from capsizing and fouling the parts of the hoisting line extending from its sheaves.

Efforts to correct this tilting tendency in the traveling blocks of apparatus hitherto utilized in drilling practice, by first reeving the outer sheaves of the traveling block, have resulted in the crossing of the parts of the line in such a manner as to set up a destructive chafing between the parts rove and in producing a "fleeting angle" between the rope grooves of the sheaves and the parts of the line extending therefrom destructive to both.

Another disadvantage is that in all compound pulley structures and methods of reeving heretofore utilized for the reeving of more than four running parts, the traveling block could not be made to hang in the center of the well, except when all of the compound pulley sheave members of both the crown and traveling block were fully rove, without resorting to shifting of the position of the crown block with respect to the center of the well, so as to unfairly load the derrick.

A further disadvantage has arisen from the fact that the structures and methods previously used result in excessive side diversion of the line from the rope grooves of the majority or all of the compound pulley sheaves.

Another disadvantage has arisen from the fact that the structures and methods of reeving previously utilized have, of necessity, limited the diameter of some of the compound pulley sheaves, either in the crown block or traveling block or in both, and thereby caused excessive bending stresses in the hoisting line, which are particularly productive of excessive wear and tear upon the wire rope which is ordinarily used for this line.

Other disadvantages have been present in prior art structures, as will appear as this description progresses.

One of the objects of this invention is to provide a hoisting apparatus embodying a compound pulley of such structure and so rove that a maximum balanced effect will be produced, so that tilting of the traveling block will be reduced to a minimum, and so that the said tilting tendency in a traveling block having three or more sheaves, when operated by a pulling force applied to one end of a single line, is not substantially greater than the tilting tendency inherent in a two-sheave traveling block when so operated, irre-

spective of the number of sheaves, in excess of two, rove and operated.

Although hoisting apparatus has heretofore been utilized in industries other than oil well drilling in which the traveling block was effectively balanced, and in which the "fleeting angle" of the parts of the flexible element rove, such as fiber ropes, chains, and wire hoisting cables, with respect to the sheaves from which they extend 10 was effectively eliminated, and undue wear and tear on the element rove was absent, all such apparatus hitherto utilized lacked the requisite combination of factors in their structure and method of reeving which would permit them to 15 be adapted to, and incorporated into, well drilling practice, as developed during the evolution thereof to its present status.

For instance, apparatus and methods of reeving heretofore utilized, in which the factor of "fleeting 20 angle" was not harmfully prevalent and in which the traveling block was effectively balanced, contemplated and provided means only adaptable to be fully rove.

This is very undesirable in hoisting apparatus 25 for use in well drilling, since, at the outset of the drilling operations, the load to be hoisted is relatively light, and speed of operation of the apparatus by reeving a minimum number of parts of the line between the crown block and the traveling block is the objective sought.

Another object of my invention is to provide a structure and method of reeving whereby a minimum of four running parts of the line may be rove and the apparatus operated with the traveling block effectively balanced and with all of the parts then rove extending from the sheaves in substantial parallelism with the grooves thereof.

Another object of my invention is to provide a structure and method of reeving in which it is 40 feasible and convenient to progressively reeve the apparatus as required in the progress of the drilling operation by adding other parts to the minimum of the parts which serve to initially reeve and balance the traveling block.

Still another objection to all previously known and utilized structures and methods of reeving in hoisting apparatus, in which the traveling block operated in an effectively balanced condition and in which the flexible element rove between the 45 fixed block and the traveling block extended from the sheaves in substantially parallel relation with respect to the grooves thereof, and a serious objection, is that the flexible element was either endless and, therefore, inadaptable to well drilling practice, or the ends could not be "fair led" off from over sheaves in the fixed block (equivalent to the crown block) to winding drum means and to anchorage means as disposed in the various conditions existent in well drilling outfits.

These anchor means are sometimes disposed on the traveling block, sometimes on another winding drum, and sometimes consist of a base sill of the derrick structure or means attached thereto.

An object of my invention is to provide a hoisting apparatus of such structure and so rove that, when utilized in combination with the conventional well derrick and with the combinations of winding drums and anchorages utilized therein, whether it be rove with a minimum of four running parts of the hoisting line, or rove with an intermediate number of parts of the line of more than four and less than the capacity of the compound pulley sheaves of the blocks, or fully rove, the ends of the hoisting line may always be fair 70 led off from over sheaves in the crown block to

the respective hoisting drums and anchorages below, the traveling block will always be effectively balanced and will always operate in the same predetermined vertical path, and a majority or all of the parts of the hoisting line between the 5 sheaves of the crown block and the sheaves of the traveling block will always be substantially parallel to the grooves of the sheaves from which they extend.

Another object of this invention is to provide 10 a hoisting apparatus embodying a compound pulley of such structure and so rove that excessive side diversion on the sheave members thereof will be substantially eliminated and that all excessive bending stresses in the line will be eliminated. 15

Another object of this invention is to provide a hoisting apparatus of such structure and so rove that it will be feasible to have all of the compound pulley sheave members of large diameter in both the crown block and traveling block, while 20 at the same time providing means whereby a traveling block having more than two sheaves may be balanced and centered under all conditions of operation and regardless of the number of plies rove, which has hitherto been impossible 25 in the art.

Other objects of this invention will appear as this description progresses.

In order to clarify and qualify the meaning of some of the terms employed, which are believed to be peculiar to well drilling practice, it is desired to here define the sense of "dead line" and "running part" as applied herein to the compound pulley hoisting line.

In the original American standard cable-drilling rig, after the introduction of sheaves in the crown block thereof intended especially as compound pulley sheaves, commonly known in well practice as the "casing" sheaves, the standing part of the compound pulley hoisting line 35 was usually and generally led off from over a compound pulley sheave in the crown block and secured to the traveling block, and the end of the part so secured was known as the "dead end".

When so secured, the standing part passes 45 through the groove of but one rotating sheave, i.e. through the groove of and over a sheave in the compound pulley sheave assembly in the crown block; however, all line parts move in either an up or down direction.

In the later American hydraulic rotary-drilling rig, the "dead end" was secured sometimes as in the practice in the standard cable-drilling rig; and again, sometimes, the "dead end" was led off from over a compound pulley sheave in the 55 crown block, instead of being secured to the traveling block structure, was anchored to a base sill of the well derrick structure, or otherwise secured independently of the traveling block.

Still later, with the advent of the combination 60 standard cable-drilling-hydraulic rotary-drilling rig, the respective ends of the single hoisting line employed in the operation of compound pulleys as utilized in well practice were each secured to individual winding drums, so that one of said 65 drums could preferably be used during the operation of the hydraulic rotary-drilling rig, while the other drum, in an emergency, could be employed; particularly, to prevent the loss of the "drill stem" of the rotary-drilling rig by "sticking" 70 or "freezing" in the well during an enforced period of vertical immobility.

Under the last two specifically cited practices in well drilling a novel condition is produced:

The line part which extends off from over a 75

sheave in the crown block and is the farthest line part extending between sheaves of the respective blocks from the fall part does not move per se in an up and down direction, but is taken 5 up and shortened and, conversely, led out and lengthened from under a traveling block sheave, and is, therefore, throughout its extension between the crown and traveling block, stationary.

This line part is, for this reason, in well practice called the "dead line", and is in reality an 10 extension of the standing part.

The terms "parts" and "plies" are used synonymously herein throughout.

The term "multiple ply tackle" as occurring 15 hereinafter shall be understood to be synonymous with compound pulley, while the term "multiple ply" used adjectively shall be taken to mean the same as compound pulley used in the same sense.

The preferred embodiment of my invention 20 contemplates the reeving of a single hoisting line through the compound pulley sheave members of the crown block and the traveling block by such a method that the traveling block may be suspended in a cradle formed by two loops of the 25 line which are opposite each other, the component parts of which extend from the outer sheaves of the traveling block.

In other words, the traveling block is, in effect, suspended from the four corners of the assembly 30 of compound pulley, or multiple ply tackle, sheave assembly of the crown block.

Furthermore, my method of reeving the line through the compound pulley sheave members of the crown block and the traveling block is such 35 that these cradle loops are formed by four running parts of the hoisting line rove in direct sequence from an end thereof, which are substantially perpendicular to the axes of the sheaves from which they extend.

40 The result of this is that, whenever during the progress of the drilling operation it becomes necessary to reeve additional running parts of the line to the compound pulley sheave members, these additional plies will be rove to the intermediate sheaves of the traveling block and will, in nowise, interfere with either the balanced effect, or the centered position of the traveling block originally created by my described method of reeving four running parts of the hoisting line 45 from an end thereof to produce the said loops.

The multiple ply hoisting tackle which I utilize in the preferred application of my method comprises a crown block with a plurality of multiple 50 ply hoisting sheave members therein and a traveling block suspended therebeneath by a single hoisting line rove a multiplicity of plies therebetween.

55 Preferably, the crown block comprises at least two multiple sheave hoisting members, one at one side of the crown block and the other at the opposite side thereof, in combination with one or more cross-wise multiple ply hoisting sheave members, with the axis thereof disposed at an angle to the axes of the two sheaves and between substantially vertical planes coincident with the opposing side of the said two sheave members.

This combination of sheaves in the crown block is designed to operate in conjunction with a traveling block having a plurality of hoisting 60 sheaves which may be so disposed that the axes of these traveling block hoisting sheaves are at a distinct angle to the axes of the first said two hoisting sheaves of the crown block.

65 Furthermore, my method and structure are such that the traveling block is not only balanced

and centered as indicated above but the multiple 5 ply hoisting sheave members of the crown block and of the traveling block are so disposed with relation to each other that the various plies of the hoisting line are in substantial parallelism with the sheave grooves from which they extend and these plies are maintained in a substantially perpendicular relation to the axes of their sheaves.

This results in a hoisting tackle wherein the traveling block is balanced and centered under 10 all conditions of operation while the fleeting angle of the parts of the line with respect to any sheaves from which they extend is such as to entirely obviate excessive side diversion and to consequently reduce wear upon the sheaves and line 15 to a minimum.

More specifically, my invention preferably comprises a crown block having at least two multiple ply hoisting sheave members, one at one side of the crown block with one of its plane 20 faces in lateral opposition thereto and the other at the opposite side thereof, and with one of its plane faces in lateral opposition thereto with the axes of these sheave members in alignment and with one or more cross-wise multiple ply hoisting 25 sheave members at an angle thereto.

The cross-wise sheave member or members may have the axis or axes thereof either above or below the axes of the other sheave members, with the cross-wise multiple ply hoisting sheave member or members disposed between vertical planes which are substantially parallel to the vertical planes in which the said first two sheave members lie. Likewise, the cross-wise sheave member or 30 members should be located with their plane faces 35 in lateral opposition to the other opposing sides of the crown block.

My invention is particularly important in connection with a multiple ply rope hoisting tackle wherein a single rope is rove with more than four 40 plies. Therefore, my apparatus preferably comprises additional sheave members disposed intermediate the vertical planes in which the two first said sheaves of the crown block lie, one at one side of the crown block and the other at the other side 45 thereof.

In conjunction with this structure of crown block, I preferably use a traveling block having more than two sheaves suitably mounted to form a symmetrical structure and having pin means 50 to support a becket on the lower end thereof.

The position of the traveling block is preferably cross-wise with respect to the first above-mentioned two sheaves at opposite sides of the crown 55 block.

With such a combination, whenever it becomes necessary to reeve more plies through the sheaves of the tackle, they may be roved through the intermediate hoisting sheave members of the traveling block.

60 From this description, it will be seen that I have provided a multiple ply hoisting tackle for a derrick and a method of reeving the same which has many important advantages. Some of these advantages have already been pointed out. For instance, one of these important advantages is the production of a multiple ply rope hoisting tackle wherein the traveling block will be properly centered and balanced by reeving the outer sheaves of the traveling block with four plies of the line roved in direct sequence from one of its ends, while as many more plies as desired may be roved through the sheaves of the tackle without destroying or disarranging this centered and balanced condition of the traveling block.

Another important advantage arises from the fact that excessive side diversion is eliminated by my invention while, at the same time, it is possible to use multiple rope hoisting sheave members in the crown block which are much larger than hitherto possible and, in fact, may extend substantially across the opening in the water-table. This greatly reduces the wear upon the rope and otherwise prolongs the life thereof. It likewise decreases bearing troubles by reducing the speed of the sheave members.

Another important advantage of my invention arises from the fact that I am able to lead the ends of my hoisting rope to different sides of the derrick, which is particularly necessary in combination rigs, this being accomplished by the use of one or more crosswise sheave members in the crown block which are also an important element in the reeving of the rope through the sheave members of the crown block in such a manner as to produce a centered and balanced traveling block and freedom from excessive side diversion.

Other objects and advantages of my invention will more fully appear from the following detailed description taken in connection with the accompanying drawings which illustrate several embodiments thereof and in which:

Figure 1 is an elevation of a combination crown block and traveling block structure embodying the features of the present invention showing it applied to a typical steel derrick top and looking at it from the ladder side of the derrick, the ladder being omitted;

Figure 2 is a side view of the structure shown in Figure 1 looking at it from the beam side of the derrick;

Figure 3 is an enlarged fragmentary sectional view of my novel traveling block structure;

Figure 4 is a fragmentary view partly in section taken on substantially the line IV—IV of Figure 3;

Figure 5 is a fragmentary plan view taken on substantially the line V—V of Figure 1 drawn to an enlarged scale and illustrating the mounting for the cross-over sheaves;

Figure 6 is a plan view of the structure as shown in Figure 2;

Figure 7 is an elevation partly in section similar to Figure 1 of a modification of the present invention mounted on a typical wooden derrick top;

Figure 8 is a side view of the structure shown in Figure 7 partly in section;

Figure 9 is a plan view of the structure shown in Figure 8;

Figure 10 is a fragmentary detail view partly in section taken on the line X—X of Figure 1 looking downwardly;

Figure 11 is a diagrammatic view illustrating the relation of the sheaves in the traveling block to each other and their position relative to the finger connected to the fourble board of the derrick;

Figure 12 is a diagrammatic view illustrating the arrangement of the lines or plies in my novel structure when a four line stringup is being used;

Figure 13 is a diagrammatic view illustrating the arrangement of the lines or laps in my structure when a six line stringup is being employed;

Figure 14 is a diagrammatic view illustrating the arrangement of the lines when an eight line stringup is being employed, and

Figure 15 is a diagrammatic view illustrating the arrangement of the lines or plies when a ten line stringup is being used.

In the drawings:

Like reference characters designate similar parts throughout the several views.

In Figure 1, 20 designates generally the upper part of a typical steel oil well derrick top which may be of any conventional construction. This derrick top includes a pair of water table beams or bumpers 27—27 mounted on the water table 21. When built according to standardized practice the net clearance between the inner edges of these water table beams 27—27 amounts to 5' and 6". The derrick also has mounted on an intermediate portion thereof, as is well known in the drilling art, a fourble board and a finger for use in connection with the stacking of pipe "stands". In Figure 11, I have illustrated diagrammatically the position of the finger relative to the center of the derrick, as will be more fully explained hereinafter in connection with a description of that figure. The finger is designated 23 generally by the reference character 23. Inasmuch as the fourble board and finger do not per se constitute a part of the present invention, and since they are well known in the art, it is thought that no further description of the same need be made.

Mounted upon the top of the water table beams 27—27 which constitute the horizontal head of the derrick is a crown block designated generally by the reference character 24 embodying the features of the present invention. Suspended from this block by means of a rope or wire line 25 is a traveling block designated generally by the reference character 26. The line 25 extends through the opening 22 (Fig. 6) in the water table and the traveling block 26 is positioned below the top of the derrick, as shown in Figure 1.

Crown block

Mounted on the top of the water table beams 27—27 are a pair of spaced transverse I-beams 28—28 disposed adjacent the center line of the derrick. Also supported upon these water table beams 27—27 are a pair of spaced I-beams 29—29 disposed parallel to the beams 28—28. The two beams 28, as best shown in Figure 6, have rotatably mounted upon them a pair of spaced pulleys 30—31 which are disposed between the beams 28—28. These two pulleys or sheaves 30 and 31 and their supporting beams 28—28 constitute the lower section of the block and properly speaking, the lower sheave means of the block as well. The sheave 30 is the cable-drilling line sheave of the standard cable-drilling rig and the sheave 31 is the sand sheave of the standard rig. These two sheaves do not per se constitute part of the present invention and are illustrated in order to show that provision is made in my novel crown block for them independently of the supporting means of the multiple ply rope tackle sheaves. The two beams 28—28 extend out a slight ways from the walking beam side of the derrick, as indicated at 32 in Figures 1 and 6. The ends of these two beams 28—28 which extend beyond the water table beam 27 on the walking beam side of the derrick are connected by a spacer 33. The sand line of the standard cable-drilling rig extends upward from the sand reel of that rig which is disposed outside of the derrick, through the space delimited by the inner sides of the beams 28—28, the inner side of the spacer 33 and the outer, upper edge of the water table beam 27, onto, through the groove of, and over the sand sheave 31 and thence downwardly to the well bore, 75

at or adjacent to the central vertical axis of the derrick, as is well known in the art.

The I-beams 29-29 rotatably carry a grooved idler pulley 34, the purpose of which will be more fully explained hereinafter. This idler is disposed on the ladder side of the derrick. Attention is directed to Figure 6 of the drawings wherein the left side thereof is the ladder side of the derrick, and the right side thereof is the forge side of the derrick and is the side on which the rotary draw works of a California combination standard cable-drilling-hydraulic-rotary drilling rig is disposed. The walking beam side of the derrick is the lower one shown in Figure 6, namely, the side to which the sand sheave 31 is adjacent. The other side of the derrick, at the top of Figure 6, to which the standard cable-drilling crown, or drilling line, sheave is adjacent, is the bull wheel side. The names by which the corners of the derrick are known are as follows: The corner formed by the intersection of the beam and ladder sides of the derrick is called the calf wheel corner; the corner at the intersection of the ladder and bull wheel sides of the derrick is the tug wheel corner; the corner formed by the bull wheel and forge side of the derrick is the brake wheel corner; while the corner at the intersection of the forge and walking beam sides of the derrick is the crane post corner. These names of the respective sides and corners of well derricks are universally known and used wherever cable-drilling and combination cable-rotary rigs are used.

Mounted upon the two water table beams 27-27 are four struts 35 which are connected and spaced from each other by pairs of horizontally disposed members, one pair of which consists of the channel members 36-36 disposed adjacent the bottom ends of the struts 35 and in parallelism with the beams 28-28, as best seen in Figure 2, while the other pair consists of the angle iron members 36a-36a disposed adjacent the top ends of the struts 35 and at right angles to the beams 28-28, as best seen in Figure 1. Supported by these struts 35 are a pair of transverse I-beams 37-37 which are disposed at right angles to the water table beams 27-27 (Figures 1 and 2). These I-beams 37 may be rigidly secured to the struts 35 in order to provide a rigid crown block. Each of these beams has mounted upon and secured to it a pair of slanting H-beams 38 which converge at their top ends, as indicated at 39 (Figure 1), where they are rigidly fastened together to provide a support for sheaves of the multiple-part rope tackle which will be described hereinafter. Each pair of H-beams 38 in reality comprises a standard for supporting sheaves. It will, of course, be understood that the set of H-beams 38 on one beam 37 is disposed parallel to the set of H-beams 38 on the other beam 37.

Extending transversely of the two I-beams 37 and mounted thereon are a pair of spaced I-beams 40 and 41. These two beams are disposed at right angles to the two beams 37. It will be noted from Figures 1 and 6 that the I-beam 41 is slightly wider than the beam 40. These two beams rotatably carry a sheave 42 disposed between them and positioned at right angles to the two standard sheaves 30 and 31. Secured to the I-beam 41 and extending upwardly therefrom are a pair of spaced vertical H-beams 43-43 which are positioned in the space between the standards 38-38. These two H-beams are inter-connected and reinforced by means of diagonal angle irons 44 (Figure 2). Each beam 43 is also reinforced by a diagonal plate 44' secured to the beam 41.

Mounted upon the top of one of the H-beams 43 and upon the top of the associated standard 38, as best shown in Figure 6, is a shaft 45 which is secured to the top of the associated standard 38 and the beam 43 by means of clamps 46 and 47, respectively. Rotatably mounted upon this shaft 45 are a pair of spaced parallel sheaves 48 and 49 between the standard 38 on the ladder side of the derrick and the associated H-beam 43.

Similarly positioned on the draw works or forge side of the derrick is a shaft 50 which is carried on top of the other standard 38 and the top of the other H-beam 43. This shaft 50 is secured to the associated standard by means of a clamp 51 and to the associated H-beam by means of a clamp 52. Rotatably mounted upon this shaft 50 are a pair of spaced parallel sheaves 53 and 54 disposed between the associated standard 38 and the associated H-beam 43. It will be noted that the two sheaves 48 and 53 are each of the same diameter and are larger in diameter than the sheaves 49 and 54. Also each of the sheaves 49 and 54 has the same diameter. These four sheaves are disposed parallel to the standard rig sheaves 30 and 31 (Figure 6).

In Figure 6 it will be observed that the shafts 45 and 50 are disposed in axial alignment. The inner ends of these two shafts are connected to couplings 55 and 56 which couple the shafts to a reinforcing tube 57 disposed centrally of the top of the crown block. As best shown in Figure 1, each shaft 45-50 has each of its ends flattened as indicated at 58. These flattened portions 58 of the shafts cooperate with the tops of the standards and the tops of the H-beams 43 to prevent rotation of these shafts. Attention is directed to the fact that one set of parallel sheaves 48-49 is disposed parallel to the ladder side of the derrick and the other set of sheaves 53-54 is disposed parallel to the draw works or forge side of the derrick. These four sheaves are disposed at right angles to the sheave 42.

In Figures 5, 6 it will be observed that a pair of spaced parallel I-beams 59 and 60 are also mounted upon the spaced beams 37-31. These two beams 59 and 60 are normally mounted at an angle to the two transverse beams 41 and 42. Disposed between the two beams 59 and 60 and rotatably carried thereby is a sheave 61 disposed parallel to the beams 59 and 60. This sheave 61 is disposed at an angle to the sheave 42. It will be observed from Figures 2 and 6 that the two sheaves 61 and 42 are disposed below the parallel sheaves 48-49 and 54-53. By positioning them below these parallel sheaves, I am enabled to make these two sheaves 42 and 61 of a much greater size than would be possible if they were positioned directly between the parallel sheaves. Also attention is directed to the fact that these two sheaves 61 and 42 extend substantially clear across the top of the water table from the ladder side of the derrick to the draw works or forge side of the derrick.

One of the beams 37 has secured to it a plate 62 upon which the beams 59 and 60 are mounted at one end. Similarly the other beam 37 has secured to its top flange a plate 63 for use in the mounting of the two beams 59 and 60. The plate 63 has a thickness substantially that of the lower flange on the I-beam 41. A diagonal plate 64 has one end secured to the top of the plate 63 and has its other end mounted upon the top of the lower flange of I-beam 41, as shown in Figure 5. The ends of the two beams 59 and 60 rest upon the top of the diagonal plate 64. Also

these beams 59 and 60 are each of less height than the I-beams 40 and 41, as best shown in Figures 1 and 5, whereby the beam 60 extends into the space separating the adjacent lateral flanges of the I-beam 41. This arrangement is such that the major part of the weight of one end of the beam 60 is disposed upon the beam 41 and the major part of the weight of one end of the other beam 59 is disposed upon the plate 63 secured to the top of one of the beams 37.

It will, of course, be understood that the plate 62 has a thickness equal to the thickness of the two plates 63 and 64 taken together. This arrangement permits disposition of the two beams 59 and 60 in a straight horizontal position relative to the beams 37. In practice, the two beams 59 and 60 are adjustably secured to the beams 37-37 so as to permit variation of the angle between the sheave 61 and the sheave 42. In other words, the sheave 61 is adjustable to and from the sheave 42. The adjustment is accomplished by removing the bolts which secure the beams 59 and 60 to the beams 37-37 and by thereafter sliding the two beams on the beams 37-37 into the desired position. After the sheave 61 has been properly placed, the two beams 59 and 60 are again rigidly secured to the beams 37 by means of the bolts.

30 Traveling block

The traveling block 26 comprises a pair of oppositely disposed sheave housings 65-66. The lower end of the housing 65 has rigidly secured to it a pivot or hinge portion 67 and the lower end of the housing 66 has rigidly secured to it a similar pivot or hinge portion 68 (Figure 4). Each of these similar pivot or hinge portions extends downwardly between spaced pivot plates 69-69 formed integral with block 70. These two hinge portions 67 and 68 are pivotally mounted upon pins 71 and 72, respectively. These pins are mounted at their ends in the two plates 69-69, as is evident from Figures 3 and 4. Extending through the block 70 is a pin 73, the ends of which project beyond the block 70 to receive a becket (not shown).

The housing 65 has mounted in it a circular container 74 adapted to receive sheaves, and the housing 66 has mounted in it a circular container 75 adapted to receive sheaves. These containers may be rigidly fastened to the housing, if it is so desired. Also it will be noted that the sides of these containers serve as guards for the sheaves therein, as best shown in Figure 3. Disposed in the container 74 of the housing 65 are a pair of spaced parallel sheaves 76 and 77, and disposed in the container 75 of the housing 66 are a pair of spaced parallel sheaves 78 and 79. The sheaves 76 and 78 are of the same diameter and the sheaves 77 and 79 which are slightly smaller in diameter than the sheaves 76 and 78 are also of the same diameter. I purposely make the sheaves 77 and 79 smaller in diameter than the other two sheaves so as to obviate side diversion of the wire line 25. The sheaves 78 and 79 are mounted upon a shaft 81 which extends through the sides of the container 75 and is mounted in the sides of the housing 66. The two sheaves 76 and 77 are mounted upon a shaft 80 mounted at its ends in the sides of the housing 65. Attention is at this time directed to Figure 11 wherein it will be noted that the sheaves 76, 77, 79 and 78 are positioned between the finger of the derrick and the beam side of the derrick and are disposed substantially parallel to the beam side

of the derrick. By having the axes of these sheaves at right angles to the length of the finger, it is possible to use relatively large sheaves without in any way reducing the size of the storage space provided for the stands of pipe in the derrick. 5

It will be noted from Figure 2 that each of the housings 65 and 66 merely comprises a pair of upwardly extending legs between which is disposed the container of the sheaves. The upper 10 edges of each of the containers 75 and 76 have rigidly fastened to them guards 82, which guards are disposed between the lines leaving the sheaves.

Positioned between the two sheave housings 15 65 and 66 is a vertical member 84 having its lower end bifurcated to form a slot 85 (Figures 3 and 4). The legs 86 defining the slot 85 in the member 84 have their lowermost extremities mounted upon the pin 73. It will be noted from Figure 4 that the inner edges of the two legs 86 embrace the plates 69-69 and the outer sides of the block 70. The upper end of the member 84 is enlarged and provided with an angular portion 87 having rigidly fastened to it a pair of 20 oppositely disposed angle irons 88. These angle irons support a U-shaped bracket 90 between the legs of which is disposed a sheave housing 91 into which the lower half of a sheave 92 extends. That is to say, the housing 91 only covers the 30 lower half of the sheave 92. The sheave 92 is disposed at an oblique angle relative to the sheaves in the housings 65 and 66. This sheave is mounted upon a pin 93 which extends through the walls of the housing 91 and is mounted in the 35 legs of the U-shaped bracket 90.

I shall now proceed to describe the hinge connections between the central member 84 and the housings 65 and 66, which connections permit of the housings pivoting outwardly in opposite 40 directions. Disposed on opposite sides of the member 84 are a pair of plates 95-95 rigidly connected together by means of a filler block 96 extending into the slot 85 of the member 84. These plates are adapted to slide up and down 45 the vertical member 84. Secured to each plate 95 is a hinge member 97 including a pin 98. Mounted upon the ends of each pin 98 are a pair of downwardly extending plates 99 which are pivotally connected at their lower ends to one of the 50 sheave housings by means of a hinge 100. It will be noted that there are two plates 99 connected to each housing 65-66. These plates 99 permit hinging movement of the housings 65 and 66 with respect to the central member 84. In 55 general, the function of the plates 95 and the filler block 96 is to guide the lateral movement of the sheave housings. Also the plates 99 serve as a means for limiting the outward movement of the sheave housings. The plates 99-99 also 60 serve to maintain the member 84 in a central position so as to prevent swaying of the sheave 92. Moreover, these plates 99 counteract each other and result in a highly balanced traveling block. In other words, the swaying of one sheave 65 housing is counteracted by the other housing, thus preventing the wire lines from riding over the rims of the sheaves carried in these housings.

Operation and stringup

70
As previously pointed out, my novel combination crown block and traveling block structure is adapted to accommodate either a four, six, eight or ten line reeving or stringup.

In practice, in accordance with the principles 75

of this invention, the traveling block will at all times, whether loaded, or without a load other than the usual hook and "pipe elevator" means normally attached to it, hang with its central vertical axis substantially coincident with the 5 vertical axis of the compound pulley standing block sheave assembly, irrespective of the number of running parts rove and utilized.

This is an outstanding result from my invention 10 since it permits the initial well drilling operation to be started with a minimum of four line parts rove between the crown and traveling block in such a manner that the traveling block is balanced and centered permanently and that the center of the well bore thus started will always be substantially co-incident with the central vertical axis of the traveling block when the latter is hanging free and unloaded with additional line parts rove. Thus, it will be seen that my present arrangement 15 is in this respect a decided improvement over the prior art, in which it is difficult if not impossible to operatively reeve a minimum of four line parts between the crown and traveling block so that a well bore started with such a reeving will be under 20 the central vertical axis of the traveling block when that block with additional line parts rove is hanging free and unloaded. Obviously the fewer the number of lines between the crown block and traveling block, the greater will be the speed of the 25 hoisting operation. The fewer the number of lines, the less will be the total wire line wear. By 30 lines is meant the number of parts of the single line 25 connecting the crown block 24 to the traveling block 26.

35 In Figure 12, as well as in Figures 13, 14 and 15, I have illustrated diagrammatically the arrangement of the sheaves in the crown block relative to the sheaves in the traveling block, as well as the arrangement of all the sheaves relative to the 40 sides of the derrick. In Figure 15 I have applied the names of the several corners and sides of the derrick so as to render apparent the arrangement of the sheaves and tangential points thereof relative to these sides and corners, so as to simplify 45 the explanation of my invention. It will be noted that the other three figures 12, 13 and 14 conform to the same focus as Figure 15, and hence, the terminology given in Figure 15 is also applicable to these other figures.

50 Now it will be evident that one end 101 of the wire line 25 is connected to the calf wheel (not shown) and the other end 102 of this line is connected to the draw works (not shown). Also it is 55 obvious that the line in passing over each sheave has two points of tangency with that sheave, namely, the point where it enters the groove in the sheave and the point where it leaves the groove in the sheave. In Figures 12, 13, 14 and 15 I have designated these tangency points by letters of 60 the alphabet. These points on sheaves 48, 49, 54 and 53 are designated by *a*—*b*, *o*—*p*, *s*—*t* and *e*—*f*, respectively. These points on sheaves 76, 77, 78 and 79 are designated by *h*—*g*, *v*—*u*, *q*—*r* and 65 *c*—*d*, respectively. Furthermore, these points on sheaves 61, 42 and 92 are designated by *i*—*j*, *m*—*n* and *l*—*k*, respectively.

In the four line stringup illustrated diagrammatically in Figure 12, the end 101 of hoisting line 25 extends upwardly in the calf wheel corner to point *a* on outer sheave 48 on the ladder side of the derrick. From point *a* the line extends over the sheave to point *b* which is adjacent the tug wheel corner, and down to point *c* on outer sheave 78 of the traveling block 26 disposed on the bull wheel 75 side of the derrick. From point *c* the line extends

under the sheave 78, up to point *d* which is adjacent the brake wheel corner, of the derrick. From point *d* the line extends upwardly to point *e* on outer crown block sheave 53 disposed on the draw works side of the derrick. After leaving point *e* the line travels over the top of sheave 53 to point *f* which is adjacent the crane post corner, and downwardly from point *f* to point *g* on outer traveling block sheave 16 disposed on the beam side of the derrick. From point *g* the cable line extends 10 under sheave 16 to point *h* which is adjacent the calf wheel corner of the derrick. The line is led from point *h* upwardly through the groove of idler 34 to point *i* on cross-over sheave 61 and over the 15 top of this sheave to point *j* disposed on the draw works side of the derrick. The idler 34 always operates on the fourth part of the line rove from an end. It serves to cause the fourth line of the stringup to be disposed symmetrical with respect to the other three lines in the region of the traveling block so as to enable the traveling block to be maintained over the center of the well. From point *j* the line end 102 extends downwardly to the draw works drum. At this time I wish to direct 20 attention that in the stringups shown in Figures 25 12 and 14, and in Figs. 13 and 15, the sheave 61 has different angular positions. This is possible due to the adjustable mounting for the sheave 61 previously described in connection with the beams 25 and 60, as best shown in Figure 5. From the 30 foregoing description of the four line stringup or reeving, it will be evident that four plies or line parts rove between the crown and traveling block constitute a minimum, operative reeving.

In the six line stringup illustrated diagrammatically in Figure 13, the hoisting line is strung exactly the same as in Figure 12 up to point *j*. From point *j* the line is extended downwardly on the draw works side of the derrick to point *k* on the intermediate sheave 92 of the traveling block. The line is then passed under the sheave 92 to point *l* and from point *l* it is extended upwardly on the ladder side of the derrick to point *m* on crown block cross-over sheave 42. After passing over the sheave 42, the line 45 leaves the sheave at point *n* and has its end 102 connected to the draw works drum.

In Figure 14 I have illustrated diagrammatically an eight line stringup. Up to point *h*, this stringup is exactly the same as that described 50 in connection with Figure 12. After leaving point *h* the line passes upwardly through the groove of the idler 34 to point *o* on the intermediate crown block sheave 49. From point *o* the line extends over sheave 49 to point *p* and down to 55 point *q* on the intermediate traveling block sheave 79. The line is led from point *q* under the sheave 79 to point *r* and from point *r* up to point *s* of intermediate crown block sheave 54. From point *s* the hoisting line extends up over sheave 54 to 60 point *t* and downwardly to point *u* of the intermediate traveling block sheave 77. After passing under this sheave 77, it leaves the sheave at point *v* and extends upwardly to point *i* on cross-over sheave 61. Thereafter the cable is 65 passed over the top of sheave 61 to point *j* and thence downwardly to the draw works drum.

The ten line stringup illustrated diagrammatically in Figure 15 is exactly the same as the stringup shown in Figure 14 up to point *j*. From 70 point *j* the hoisting line is led downwardly to point *k* of the intermediate sheave 92 of the traveling block. The line is then passed under the sheave 92 to point *l* and from point *l* on the ladder side of the derrick upwardly to point 75

m of cross-over sheave 42 in the crown block. From point *m* the line is passed over sheave 42 to point *n* and from point *n* the line extends down to the draw works drum.

- 5 It will be noted that the ends 101 and 102 of the hoisting line 25 after leaving the crown block are led directly to the two hoisting drums on the adjacent sides of the derrick. In order 10 to permit the calf wheel end of the line 101 to be led directly to the calf wheel, I have provided one of the water table beams 21 (Figure 10 10) with a slotted portion 105 through which the wire end 101 extends. This permits the end 101 to extend in a direction substantially parallel 15 to the beam side of the derrick.

In my novel crown block it will be observed 20 that it is designed so as to facilitate the installation and removal of the standard ring sheaves and so that these sheaves and their supporting 25 means may be removed and the supporting means of the multiple part rope tackle sheaves left intact and the sheaves of those sets operative without the removal of any interconnecting parts. And, the multiple part rope tackle sheaves and 30 their supporting structure, including the grooved idler pulley 34 and its supporting beams 28-29, may likewise be removed and the lower sheave means and their supporting means left intact and operative without the removal of any inter- 35 connecting parts relative to the multiple ply rope hoisting sheave supporting structure. Then, too, it is to be remembered that although all of the sheaves in the crown block are of relatively large size, namely 48" in diameter or more, the block 40 is not of a greater size than can be accommodated in the limited space afforded in the top of the standard type of derrick. The lines extending downwardly from the sheaves in the crown block are so disposed that they will not 45 bind on the edges of the water table beams defining the 5' 6" opening between them. That is to say, the design of the crown block is such that it can be used in conjunction with a standard opening of 5' 6" between the water table

beams.

The relatively large sheaves in the crown block are so arranged that the entire external surface of the hoisting line contacts with the peripheries of the sheaves during operation so that the wear 50 will be proportionately distributed over the entire surface of the line.

By disposing some sheaves in the crown block at right angles to those in the traveling block, I find that I am enabled to get a symmetrical rope arrangement which is highly desirable in that it minimizes the wear and tear upon the line and enables side diversion to be obviated. It is to be understood that in all cases the parts of the hoisting line are disposed parallel 60 to the grooves of the associated sheaves from which they extend. This is true irrespective of the number of lines or plies employed. For example, in Figure 2 it will be observed that the lines leaving the sheaves in 65 the crown block are disposed parallel to the grooves in the sheaves. In the lower part of Figure 1 it will be observed that the lines extending from the sheaves in the traveling block are disposed parallel to the grooves of the 70 associated sheaves. This desirable result is due to the pivotal mountings provided for the sheaves. Due to this structure, any sheave so mounted is adapted to automatically adjust itself to the 75 direction of the line parts extending therefrom so that the side edges of the groove thereof

will be disposed parallel to the lines. Obviously by having each line parallel to the groove of the sheave through which it passes, side diversion of the line is necessarily eliminated and, hence, the wear and tear on both the rope and the rim of the sheave is minimized. From Figure 12 it will, of course, be evident that the lines or plies of the single line 25 are disposed at right angles to the common axis of the two shafts 45 and 50. Similarly the lines leaving the 10 casing 75 of the traveling block 26 are disposed at right angles to the axis of shaft or pin 81. Also the lines emanating from the casing 74 are disposed at right angles to the axis of the pin or shaft 80.

15 By arranging one or more of the sheaves of the crown block at substantially right angles to a vertical grooved face of the traveling block the sheaves in the traveling block and one or more sheaves in the crown block crosswise to the first 20 mentioned sheave means therein and disposed transversely of the traveling block structure, and using my method of reeving, I am enabled to have a balanced construction which will insure that the traveling block will move up and down without tending to tilt. The plies of rope on one side of the construction shown in Figure 2 are balanced against the plies of rope on the other side of the construction and as a result the wear and tear upon the sheaves and their bearings is greatly reduced. At this time I wish to direct attention to the fact that the distance between the vertexes of the grooves of the large pair of outer sheaves 48 and 53 of the crown block is equal to the groove diameter, i. e., the distance from the vertex of the 30 groove on one side of the sheave to the vertex of the groove on the other side of the sheave, of each of the large outer sheaves 76 and 78 in the traveling block. Similarly the distance between the vertexes of the grooves of the smaller or inner sheaves 49 and 54 of the traveling block 24 is equal to the inner diameter of the inner sheaves 77 and 79 of the traveling block 26. This permits the parts or plies of the single line 25 to be disposed in parallel relationship, as shown in Figure 2. 40 Also in my construction, due to the arrangement of the sheaves relative to each other, the line 25 is first bent in one direction and then in a direction at right angles thereto instead of in a reverse direction relative to the first mentioned direction 50 of bending, as has been the practice heretofore, thus giving a more even distribution of the bending stresses imposed on the structure of the hoisting line. Half of the bends in the lines of my construction is disposed in one direction and the other half of the bends is disposed in a direction at right angles to the same. By providing a balanced traveling block, the tendency of the traveling block to tip sidewise, due to the arrangement of the fast lines on the intermediate sheaves of 60 the traveling block and the slower lines on the outer sheaves of the traveling block, when the pulling of the line is being accomplished by the rotary draw works drum, is greatly reduced. Another advantage of the balanced traveling block 65 is that undesirable swaying of the block, which would cause it to strike the finger as the block is moved up and down, is eliminated. Of course, it must be understood that when the rotary draw works is being used to operate the traveling block, 70 the dead line and the slowest moving line will be positioned adjacent the finger 23, which is desirable since it protects the derrick man on the fourble board in the event that he should accidentally grab one of the lines adjacent the finger. 75

Modified form of invention

In Figures 7, 8 and 9 I have illustrated a modification of my invention which is not quite as desirable as the preferred form inasmuch as the cross-over sheaves in the crown block are positioned above and between the other sheaves in the crown block and as a result cannot be made as large as the cross-over sheaves in the preferred form of the device. The derrick 120 is of a conventional wooden type and includes a top or water table 121 having an opening 122 and wooden table beams 130-130. This derrick employs the conventional type of finger and fourble board (not shown) such as are well known in the derrick art. Mounted upon this derrick is a crown block 124 and a traveling block 26. Inasmuch as the traveling block 26 is identical in construction to the traveling block previously described in connection with Figures 3 and 4, no further description of this block is thought necessary. However, it is to be noted that the same reference characters have been applied to the parts comprising the block as were used in connection with the description of the block shown in Figure 3. I shall now proceed to describe in detail the modified form of crown block 124 used in this modification of the invention.

Modified form of crown block

Mounted upon each of the water table beams 130-130 is a pair of fabricated sill or base structures 131, which structures are disposed parallel to each other. Positioned transversely of these structures 131-131 and rigidly secured thereto are four transverse parallel I-beams 132 which support the multiple part rope sheaves which will be described hereinafter. Positioned adjacent the ladder side of the derrick is an idler 134 which is rotatably carried by a shaft 135 connected to the underside of two of the transverse I-beams 132 (Figures 7 and 9). Each of the structures 131 is provided with a slot 133. Mounted in these slots 133 are a pair of spaced parallel I-beams 134. These beams are suitably anchored to the structures 131. It will be noted from Figure 9 that these two beams are positioned between the vertical planes in which the innermost pair of I-beams 132 lie. These beams support the two standard sheaves 135 and 136 which are rotatably mounted between the two beams, and are secured to the base structure of the crown block 131-131, as is evident, independently of the supporting means for the transversely disposed upper sheave means 142, and 161, and of the supporting means of the sheaves 148-149 and 153-154 which are disposed in parallelism with them. The sheave 135 is the drilling line sheave of the standard rig and the sheave 136 is the sand line sheave of the standard rig, and this beam and sheave assembly is adapted to be detached, at will, as a unit from the fabricated beams 131-131 which comprise the base structure of the crown block so as to leave the multiple part tackle sheaves of the crown block, including the grooved idler pulley, intact and operative. At one side of the derrick the two beams 134 project outwardly and are connected by means of a spacer 137. The sand line is led up to the sand sheave 136 between the spacer 137, the inner edges of the beams 134-134 and the upper outer edge of the fabricated structure 131 onto the sand sheave 136, over same and thence down to the well bore.

Rotatably mounted upon the tops of the beams 132 are two pairs of parallel sheaves 148, 149,

154 and 153. The sheaves 148 and 153 are of the same diameter but are larger in diameter than the two sheaves 154 and 149 which latter sheaves are also of the same diameter. These sheaves are connected by a cable line 125 to the corresponding sheaves in the traveling block 26. Inasmuch as the stringups employed in the present modification are substantially identical to those employed in the preferred form of my invention, I shall not describe the stringups any further. Secured to the tops of two of the transverse beams 132 are a pair of I-beams 139 and 140 which are disposed at right angles to the parallel sheaves previously described and in parallelism with the water table beams of the derrick 127-127, beam 1540 being supported by and secured to block means on the tops of the inner journals for the parallel sheaves 148, 149, 154 and 153, while the beam member 139 is disposed directly on and secured to the beam 132. Rotatably carried by and disposed between these two I-beams 139 and 140 is a cross-over sheave 142 disposed at right angles to the parallel sheaves.

Also secured to the inner pair of beams 132 are a pair of parallel I-beams 159 and 160 disposed at an oblique angle to the sheave 142. These two beams rotatably carry a cross-over sheave 161. I preferably provide the beams with bolts 159a and 160a by means of which they are secured to the top flanges of the beams 132-132, as best seen in Figure 8. In order to provide for adjustment of the sheave 161 to meet different conditions of reeving, different sets of apertures for the reception of the bolts 159a and 160a are formed through the flanges of the beams 160 and 132-132. In Figures 8 and 9 the bolts 159a and 160a are shown applied to secure the beams 159 and 160 in one position of adjustment, while in Figure 9 is shown part of an alternate set of apertures 162 which are provided for the reception of the bolts 159a and 160a to secure the beams 159 and 160 in another position of adjustment. The remainder of the alternate set of apertures 162 cannot be seen in the drawings because they are hidden beneath the beams 159 and 160. It will be noted from Figure 9 that the crown block arrangement of the modification is very similar to that shown in Figure 6. The principal difference between the modified form of crown block 124 and the preferred crown block 24 is that the cross-over sheaves extend above the parallel sheaves in the modification instead of below the parallel sheaves, as shown in the preferred form. As previously pointed out, the advantage of the preferred form is that it permits the use of larger cross-over sheaves. It will be evident, by comparing Figures 7 and 8 with 1 and 2, that the stringup in both forms of the invention is the same. Incidentally it will be noted that in each case I have illustrated a ten part or ply reeving inasmuch as this brings into play all of the multiple ply rope sheaves shown in the crown block and all of the sheaves of the traveling block.

When a reeving is being employed which does not require the use of the center sheave 92 in the traveling block 26, the housing 91 carrying this sheave may be readily detached from the member 84, as is evident from the disclosure in Figure 3. The connecting plates 99 not only serve to maintain the sheave 92 in a proper central position, but also serve in the event that the line breaks on one of the traveling block sheaves to limit the outward movement of the traveling block housing which is set free by the breaking

of the wire line. Lastly, as previously pointed out, these brace plates 99 tend to cause one traveling block to be balanced against the other, thus operating to cause the traveling block to hang plumb with respect to the center of the well.

It is to be understood that when an ordinal number is applied to any of the running parts of the hoisting line, that the sequence of the reeving is counted from the end of the line which is not freed to effect changes in the number of line parts utilized.

From this description, it will be seen that I have provided a multiple ply hoisting tackle for a derrick and a method of reeving the same which has many important advantages.

Some of these advantages have already been pointed out. For instance, one of these important advantages is the production of a multiple ply rope hoisting tackle wherein the traveling block will be properly centered and balanced by reeving the outer sheaves of the traveling block with four plies of the line rove in direct sequence from one of its ends, while as many more plies as desired may be rove through the sheaves of the tackle without destroying or disarranging this centered and balanced condition of the traveling block.

Another important advantage arises from the fact that excessive side diversion is eliminated by my invention while, at the same time, it is possible to use multiple rope hoisting sheave members in the crown block which are much larger than hitherto possible and, in fact, may extend substantially across the opening in the water-table.

This greatly reduces the wear upon the rope and otherwise prolongs the life thereof. It likewise decreases bearing troubles by reducing the speed of the sheave members.

Another important advantage of my invention arises from the fact that I am able to lead the ends of my hoisting rope to different sides of the derrick, which is particularly necessary in combination rigs, this being accomplished by the use of one or more crosswise sheave members in the crown block which are also an important element in the reeving of the rope through the sheave members of the crown block in such a manner as to produce a centered and balanced traveling block and freedom from excessive side diversion.

It will be understood that my invention is applicable either to standard drilling rigs, rotary drilling outfits or combination rigs.

Now I desire it understood that although I have illustrated and described in detail the preferred forms of my invention, the invention is not to be thus limited, but only in so far as defined by the scope and spirit of the appended claims.

I claim as my invention:

1. In combination with a hoisting line, a crown block structure having a plurality of rotatably mounted multiple ply rope hoisting sheave members and a traveling block structure embodying sheaves pivotally mounted so that they may swing to maintain their grooves in parallelism with the plies of the hoisting line.

2. In combination with a hoisting line, a crown block structure and a traveling block structure embodying sheaves pivotally mounted so that they may swing to maintain their grooves in parallelism with the plies of the hoisting line.

3. In combination with a hoisting line, a crown block structure and a traveling block structure,

some of the sheaves of one of these structures being at right angles to some of the sheaves of the other structure and one of the said structures having sheaves pivotally mounted so that they may swing to maintain their grooves in parallelism with the plies of the hoisting line.

4. In combination with a hoisting line, a crown block structure and a traveling block structure, some of the sheaves of one of these structures being at right angles to some of the sheaves of the other structure and one of the said structures having sheaves pivotally mounted so that their diametrically opposed vertical grooved peripheral faces may swing into tangential relation to the sheaves mounted at right angles thereto.

5. In combination with a hoisting line, a crown block structure having a plurality of rotatably mounted multiple ply rope hoisting sheave members and a traveling block structure, some of the sheaves of one of these structures being cross-wise to some of the sheaves of the other structure and one of the said structures having sheaves pivotally mounted so that they may swing to maintain their grooves in parallelism with the plies of the hoisting line.

6. In combination with a hoisting line, a crown block structure having a plurality of rotatably mounted multiple ply rope hoisting sheave members and a traveling block structure, some of the sheaves of one of these structures being cross-wise to some of the sheaves of the other structure and one of the said structures having sheaves pivotally mounted so that they may swing into tangential relation to the sheaves mounted at right angles thereto.

7. The combination of a crown block having a plurality of rotatably mounted multiple ply rope hoisting sheave members and a traveling block having a plurality of hoisting sheaves, rove with a multiplicity of plies of a single rope comprising a cross-wise multiple ply rope sheave member at an angle to that pair of sheaves of the crown block which are first rove from an end of the said line.

8. In combination with a hoisting line, a crown block having a plurality of rotatably mounted multiple ply rope hoisting sheave members and a traveling block having a sufficient number of sheaves to permit the reeving of four or more plies of the hoisting line between said crown block and said traveling block, the first five sheaves to be rove embodying a sheave at an angle to certain of the hoisting sheaves.

9. In combination with a hoisting line, a crown block having a plurality of rotatably mounted multiple ply rope hoisting sheave members and a traveling block having a sufficient number of sheaves to permit the reeving of more than four plies of the hoisting line between said crown block and said traveling block, and means permitting the reeving of the first four plies in such position that all subsequent plies will be between the first four plies rove and all plies will be substantially perpendicular to the axis of the sheaves.

10. In combination with a hoisting line, a crown block and a traveling block having a sufficient number of sheaves to permit of more than four plies of the hoisting line between said crown block and said traveling block, and means permitting the reeving of the first four plies in such position that all subsequent plies will be between a pair of the first four plies rove.

11. In a hoisting apparatus, the combination

with a crown block structure having a plurality of upright rotatably mounted sheaves lying in vertical planes, of a traveling block structure correlated therewith and having outer sheaves and one or more intermediate sheaves, all of said traveling block sheaves being disposed so that diametrically opposite points on the grooved peripheries thereof are substantially coincident with a certain two of the opposite upright sides of the traveling block structure, a hoisting line rove four or more parts between the sheaves of the respective blocks, the crown block comprising initial sheave means disposed to receive an end of said line and deliver a first running part to a first peripheral point on one of the outer sheaves of the traveling block structure on one of the said certain sides thereof, sheave means lying in a vertical plane substantially crosswise of the peripheral points of the traveling block sheaves which are coincident with the other of the said certain sides of the traveling block structure to receive from a second peripheral point on the aforesaid outer sheave of the traveling block on the second named side thereof a second running part and deliver a third running part to a first peripheral point on the other outer sheave and on the said second named side of the traveling block structure, and further sheave means in the crown block structure lying in vertical planes each of which is at an angle to the vertical plane in which the second named sheave means therein lies and on the traveling block side of the said second named sheave means to receive other running parts of the hoisting line, including a fourth part from the aforesaid end which extends from a second peripheral point on the second said outer sheave of the traveling block and from the first said side of the traveling block structure so as to permit the said traveling block to be operatively supported by two opposed loops the component parts of which extend from opposite sides of the outer sheaves thereof and to permit other running parts of the line, additionally of the said four parts rove in direct sequence from an end to form the two said loops, to be rove to intermediate sheave means of the traveling block and to extend from peripheral points thereon substantially coincident with the aforesaid pair of opposite sides thereof with all parts of the line between the sheaves of the said blocks in substantial parallelism with the grooves of the sheaves from which they extend and to also permit the ends which constitute the standing part and the fall part of the line to be led fair off from over the initial sheave means in the crown block and from a sheave member of the last named sheave means therein to winding drum means and anchor means below.

12. In a crown block for use on a derrick, a plurality of spaced upright sheaves disposed on either side of a gap which extends a substantial distance centrally intermediate inner plane faces of the component sheaves, with three or more points on their upright grooved faces substantially equidistant from a center point, a plurality of crossover sheaves having their axes positioned between vertical planes coincident with the sides of said gap, each of said crossover sheaves being disposed at an angle to the first said sheaves, and a plurality of standard rig sheaves, with their plane faces positioned in substantial parallelism with the sides of said gap, with one or more of their inner upright grooved faces adjacent to the longitudinal center of said gap, and means for rotatably supporting all of said sheaves.

13. In a crown block construction for oil derricks, the combination of a plurality of sheaves, means for rotatably supporting said sheaves comprising a lower section of the block mounted on a base, a supporting structure independently mounted on said base and extending above the horizontal plane of the said sheaves to support beams disposed transversely and astraddle of said lower section, and upper sheave means comprising sheaves journaled in spaced bearings secured to said transverse beams directly above the first said sheaves and sheaves disposed parallel to first said sheaves, at least one of the sheaves secured to said transverse beams being in a vertical plane directly above and substantially perpendicular to the vertical planes of the first said sheaves.

14. In a crown block construction for oil derricks, the combination of a plurality of sheaves, means for rotatably supporting said sheaves comprising a lower section of the block mounted on a base, a supporting structure independently mounted on said base and extending above the horizontal plane of the said sheaves to support beams disposed transversely and astraddle of said lower section, and upper sheave means comprising sheaves journaled in spaced bearings secured to said transverse beams directly above the first said sheaves, and sheaves disposed parallel to first said sheaves, at least one of the sheaves secured to said transverse beams being in a vertical plane directly above and substantially perpendicular to the vertical planes of the first sheaves, the first named supporting means being adapted to be detached from said base so as to leave the second named supporting means operatively intact.

15. In a crown block for use on a derrick, a plurality of substantially parallel sheaves disposed substantially parallel to the ladder and draw works sides of the derrick, a mounting for said sheaves for supporting them in spaced relationship, and a plurality of cross-over sheaves carried by said mounting having their axes disposed between said parallel sheaves including a sheave disposed at substantially right angles to the parallel sheaves and a sheave disposed at an angle to said other cross-over sheave, said cross-over sheaves extending from the draw works side of the derrick to the ladder side of the derrick.

16. In a crown block for use on a derrick, a plurality of parallel sheaves disposed parallel to the ladder and draw works sides of the derrick, a cross-over sheave disposed at an angle to said parallel sheaves and extending from the draw works side of the derrick to the ladder side, and an adjustable mounting for said cross-over sheave for enabling said sheave to be adjusted to a plurality of different positions whereby the angle between it and the parallel sheaves may be varied.

17. In a crown block for use on a derrick, a plurality of parallel sheaves disposed parallel to the ladder and draw works sides of the derrick, a cross-over sheave disposed at an angle to said parallel sheaves and extending from the draw works side of the derrick to the ladder side, an adjustable mounting for said cross-over sheave for enabling said sheave to be adjusted to a plurality of different positions whereby the angle between it and the parallel sheaves may be varied, and a second cross-over sheave disposed at right angles to said parallel sheaves and disposed parallel to the bull wheel and beam sides of the derrick.

18. In a crown block for use on a derrick, a plurality of spaced parallel sheaves, and cross-over sheaves having their axes positioned between said parallel sheaves including a sheave disposed at right angles to the parallel sheaves and a sheave disposed at an angle to said aforementioned cross-over sheave, all of said sheaves being of a relatively large diameter.
19. In a crown block for use on a derrick, a plurality of spaced parallel sheaves, a plurality of cross-over sheaves having their axes positioned between said parallel sheaves, each of said cross-over sheaves being disposed at an angle to said parallel sheaves, a plurality of standard rig sheaves positioned below said parallel sheaves, including a drilling sheave and a sand sheave, and an idler positioned adjacent said standard rig sheaves for cooperation with one of said parallel sheaves.
20. 20. In a crown block for use on a derrick, a plurality of sets of parallel sheaves, each set including an outer sheave and an inner sheave, the inner sheaves being of a smaller diameter than the outer sheaves, and a cross-over sheave positioned between said sets of parallel sheaves and disposed at an angle to said parallel sheaves.
21. In a crown block for use on a derrick, a plurality of sets of parallel sheaves, each set including an outer sheave and an inner sheave, the inner sheaves being of a smaller diameter than the outer sheaves, a cross-over sheave having its axis positioned between said sets of parallel sheaves and disposed at an angle to said parallel sheaves, and an adjustable mounting for said cross-over sheave for enabling the angle between said sheave and said parallel sheaves to be varied, said parallel sheaves being disposed substantially parallel to the ladder and draw works sides of the derrick and said cross-over sheave extending from the ladder side of the derrick to the draw works side.
22. In a crown block for use on a derrick, a plurality of parallel sheaves, a shaft for each of said sheaves, said shafts being disposed in axial alignment, and a reinforcing tube for coupling the inner ends of said shafts together, said tube extending between said parallel sheaves.
23. In a crown block for use on a derrick, a plurality of parallel sheaves, a shaft for each of said sheaves, said shafts being disposed in axial alignment, a reinforcing tube for coupling the inner ends of said shafts together, said tube extending between said parallel sheaves, and a cross-over sheave positioned below said tube and extending below said parallel sheaves, said cross-over sheave being disposed at an angle to said parallel sheaves and extending from the ladder side of the derrick to the draw works side.
24. In a crown block for use on a derrick, a plurality of parallel sheaves, a shaft for each of said sheaves, said shafts being disposed in axial alignment, a reinforcing tube for coupling the inner ends of said shafts together, said tube extending between said parallel sheaves, and a plurality of cross-over sheaves positioned below said tube and between said parallel sheaves, one of said cross-over sheaves being disposed parallel to said tube and the other cross-over sheaves being disposed at an angle to said aforementioned cross-over sheave.
25. In a combination crown block and traveling block structure, a crown block including a plurality of spaced parallel sheaves and a cross-over sheave disposed at an angle to said parallel sheaves and having its axis disposed between
- said parallel sheaves, a traveling block including a plurality of sheaves disposed at substantially right angles to the parallel sheaves in said crown block, and a line including a plurality of plies for connecting the sheaves in said traveling block to the sheaves in said traveling block, each ply of said line being disposed at right angles to the axis of one of said crown block sheaves and at right angles to the axis of one of said traveling block sheaves.
26. In a combined crown block and traveling block structure, a crown block including a plurality of spaced parallel sheaves and a cross-over sheave disposed between and at an angle to said parallel sheaves, a traveling block including a plurality of spaced sheaves disposed at right angles to the parallel sheaves in said crown block and an intermediate sheave disposed at an angle to said spaced sheaves, and a line including a plurality of plies connecting the sheaves of one block to the sheaves of the other block, each ply of said line being disposed parallel to the grooves of both a crown block sheave and a traveling block sheave whereby the two points of tangency of said ply relative to said sheaves are connected by a straight line, said plies of said line being so arranged as to define an inverted frusto-pyramid.
27. In a combined crown block and traveling block structure, a crown block including two spaced pairs of parallel sheaves, each pair including an outer sheave of a larger diameter than the inner sheave, a traveling block including a spaced pair of sheaves disposed at substantially right angles to the parallel sheaves of said crown block, each pair including an outer sheave and an inner sheave, the outer sheave being of a larger diameter than the inner sheave, and a line including a plurality of plies connecting the sheaves of one block to the sheaves of the other block, the outer sheaves of said crown block being connected to the outer sheaves of said traveling block and the inner sheaves of the crown block being connected to the inner sheaves of the traveling block by said plies.
28. In a combined crown block and traveling block structure for use on a derrick, a crown block including a plurality of spaced parallel sheaves disposed parallel to the ladder and forge sides of the derrick and a cross-over sheave positioned between and at an angle to said parallel sheaves extending from the draw works side to the ladder side of the derrick, a traveling block including a plurality of spaced sheaves disposed at substantially right angles to the parallel sheaves of said crown block and a sheave positioned above and at an angle to said other sheaves of the traveling block, said spaced sheaves of the traveling block being disposed substantially parallel to the bull wheel and beam sides of the derrick, and a line including a plurality of plies connecting the sheaves of one block to the sheaves of the other block, said line being adapted to be arranged so as to have four, six, eight or ten plies between said blocks.
29. In a combination crown block and traveling block structure for use on a derrick, a crown block including spaced parallel sheaves disposed parallel to the ladder and draw works sides of the derrick, a cross-over sheave positioned between and at an angle to said parallel sheaves, said cross-over sheave extending from the draw works side to the ladder side of the derrick, a traveling block including a plurality of spaced sheaves disposed substantially at right angles to the parallel sheaves of said crown block, and a

line including a plurality of plies connecting the sheaves of one block to the sheaves of the other block, each of said parallel sheaves of the crown block having its groove disposed parallel to a ply 5 of the line, which ply is also parallel to the groove of a spaced sheave in the traveling block whereby the points of tangency of the ply with the associated sheaves are connected by a straight line.

30. In a combination crown block and traveling block structure for use on a derrick, a crown block including a plurality of spaced parallel sheaves disposed parallel to the ladder and draw works sides of the derrick, a cross-over sheave disposed between and at an angle to said parallel 10 sheaves extending from the draw works side to the ladder side of the derrick and an idler disposed below said parallel sheaves, a traveling block including a plurality of spaced sheaves disposed at substantially right angles to the parallel sheaves of the crown block, and a line including a plurality of plies connecting the sheaves of one block to the sheaves of the other block, said idler 15 engaging the fourth ply of said line to cause the plies to extend from the traveling block in a 20 symmetric relation and to relieve the traveling block sheave associated with said ply from undue strains and pressure.

31. In a combination crown block and traveling block structure for use on a derrick, a crown 30 block including a plurality of spaced parallel sheaves disposed parallel to the ladder and draw works sides of the derrick, a cross-over sheave disposed between and at an angle to said parallel sheaves extending from the draw works side to the ladder side of the derrick and an idler disposed below said parallel sheaves, a traveling block including a plurality of spaced sheaves disposed at substantially right angles to the parallel 35 sheaves of the crown block, and a line including a plurality of plies connecting the sheaves of one block to the sheaves of the other block, said idler engaging the fourth ply of said line to cause the plies to extend from the traveling block in a 40 symmetric relation and to relieve the traveling block sheave associated with said ply from undue strains and pressure, said spaced sheaves of the traveling block being pivotally mounted whereby they are enabled to automatically adjust themselves to the direction of the plies so as to have 45 their grooves disposed parallel to the respective plies extending from the traveling block.

32. In a combination crown block and traveling block structure for use on a derrick, a crown 50 block including a plurality of spaced parallel sheaves and a cross-over sheave positioned between and at an angle to said parallel sheaves, a traveling block including a plurality of sheave supports, means for pivotally connecting the lower ends of said supports together whereby the upper ends of said supports are free to move to and from each other and a plurality of sheaves carried by said sections, said sheaves being disposed at substantially right angles to the parallel sheaves of said crown block and in planes which 55 converge downwardly, and a line including a plurality of plies connecting the sheaves of one block to the sheaves of the other block.

33. In a combination crown block and traveling block structure for use on a derrick, a crown 60 block including a plurality of spaced parallel sheaves and a cross-over sheave positioned between and at an angle to said parallel sheaves, a traveling block including a plurality of sheave supports, means for pivotally connecting the lower 65 ends of said supports together whereby the

upper ends of said supports are free to move to and from each other and a plurality of sheaves carried by said sections, said sheaves being disposed at substantially right angles to the parallel sheaves of said crown block and in planes which 70 converge downwardly, and a line including a plurality of plies connecting the sheaves of one block to the sheaves of the other block, each of said plies being disposed at substantially right angles to the axis of the sheaves over which it extends whereby the grooves of the sheaves are parallel to the ply.

34. In a combination crown block and traveling block structure for use on a derrick, a crown block including spaced parallel sheaves and a cross-over sheave disposed between and at an angle to the parallel sheaves, a traveling block including a plurality of relatively movable sheave supports, a plurality of spaced sheaves carried 15 by said supports disposed at substantially right angles to the parallel sheaves of said crown block and a central sheave disposed between and connected to said sheave supports, said central sheave being disposed at an angle to said spaced sheaves 20 of the traveling block, and a line including a plurality of plies connecting the sheaves of one block to the sheaves of the other block.

35. In combination with a hoisting line, a crown block structure having a plurality of upright rotatable sheaves and comprising sheave means 30 adapted to be disposed and rotate in a vertical plane obliquely angular to the vertical planes in which all of the other sheaves thereof lie, and a traveling block structure having a plurality of 35 upright rotatable sheaves and comprising sheave means adapted to be disposed and rotate in a vertical plane obliquely angular to the vertical planes in which all of the other sheaves thereof lie.

36. In a hoisting apparatus of the character including a crown block having a plurality of upright rotatable sheaves, a traveling block having a sufficient number of sheaves to permit the reeving of four or more parts of a hoisting line, a hoisting line rove a multiplicity of parts between 40 the sheaves of said blocks, a sheave in one of said blocks to be rove with said hoisting line secured in a vertical plane obliquely disposed to the vertical planes in which all other sheaves in the said 45 blocks lie, means for rotatably supporting said obliquely disposed sheave, and means for rotatably supporting all of the other sheaves in said blocks.

37. A crown block including a lower section 50 adapted to be mounted directly on the water table beams of an oil well derrick, and an upper section adapted to be mounted directly on the water table beams of the derrick to extend transversely of the lower section, the upper section including a beam, means for supporting the beam above the lower section, a sheave, and means for supporting the sheave on the beam.

38. A crown block adapted to be mounted on the water table beams of an oil well derrick including two sections to be mounted directly on said beams, one section being astraddle of and extending directly over the other and being detachable from the water table beams independently of the other, and sheaves carried by the sections, comprising sheaves of one section transversely disposed relative to the sheaves of the other section.

39. A crown block adapted to be mounted on the horizontal head at the top of a derrick including two sections to be mounted directly on the head, one section extending directly over the other and being detachable from the head inde- 75

pendently of the other, and sheaves carried by the sections, the sheaves of one section being transversely disposed relative to the sheaves of the other section.

5 40. A crown block adapted to be mounted on the horizontal head at the top of a derrick including two sections to be mounted directly on the

head, one section extending directly over the other and being detachable from the head independently of the other, a sheave carried by the upper section, and a mounting for the sheave whereby it is adjustable in opposite directions 5 horizontally.

HARRY T. NICHOLS.
